COMBINATION FURROW FORMING, SEED PLANTING, FURROW CLOSING AND WEEDING TOOL

Wallace E. Atkinson, Petersburg, Va., assignor to Long Manufacturing Company, Inc., Petersburg, Va.

Filed June 24, 1975, Ser. No. 589,754

Term of patent 14 years

Int. Cl. D8—01

U.S. Cl. D8—13

FIG. 1 is a perspective view of a combination furrow forming, seed planting, furrow closing and weeding tool, showing my new design;

FIG. 2 is a front elevation view thereof;

FIG. 3 is a side elevation view thereof, the opposite side being substantially the mirror image thereof;

FIG. 4 is a rear elevation view thereof;

FIG. 5 is a top view thereof; and

FIG. 6 is a bottom view thereof.

I claim:

The ornamental design for a combination furrow forming, seed planting, furrow closing and weeding tool, as shown and described.
